(57) **CLAIM**

The ornamental design for a level indicator, as shown and described.

DESCRIPTION

FIG. 1 is an isometric view of a first level indicator showing my new design;

FIG. 2 is a front view thereof;

FIG. 3 is a right side view thereof;

FIG. 4 is a bottom view thereof, a top view being a mirror image thereof;

FIG. 5 is a left side view thereof;

FIG. 6 is a rear view thereof;

FIG. 7 is an isometric view of a second level indicator showing my new design;

FIG. 8 is a front view thereof;

FIG. 9 is a right side view thereof;

FIG. 10 is a bottom view thereof, a top view being a mirror image thereof;

FIG. 11 is a left side view thereof;

FIG. 12 is a rear view thereof;

FIG. 13 is an isometric view of portions of a third level indicator showing my new design;

FIG. 14 is a front view thereof;

FIG. 15 is a right side view thereof, a left side view being a mirror image thereof;

FIG. 16 is a bottom view thereof, a top view being a mirror image thereof;

FIG. 17 is a rear view thereof;

FIG. 18 is an isometric view of portions of a fourth level indicator showing my new design;

FIG. 19 is a front view thereof;

FIG. 20 is a right side view thereof;

FIG. 21 is a bottom view thereof, a top view being a mirror image thereof;

FIG. 22 is a left side view thereof;

FIG. 23 is a rear view thereof;

FIG. 24 is an isometric view of portions of a fifth level indicator showing my new design;

FIG. 25 is a front view thereof;

FIG. 26 is a right side view thereof, a left side view being a mirror image thereof;

FIG. 27 is a bottom view thereof, a top view being a mirror image thereof; and,

FIG. 28 is a rear view thereof.

The broken lines shown in FIGS. **1-28** illustrate portions of the level indicators and form no part of the claimed design. The separation and bracket shown in FIGS. **13-15** and **17** form no part of the claimed design and are provided to illustrate that the precise length of the tube assembly of the third level indicator is not claimed.

The separations and brackets shown in FIGS. **18-20**, **22** and **23** form no part of the claimed design and are provided to illustrate that the precise lengths of the heads of the fourth level indicator are not claimed.

The separations and brackets shown in FIGS. **24-26** and **28** form no part of the claimed design and are provided to illustrate that the precise lengths of the tube assembly and the heads of the fifth level indicator are not claimed.

The hatching pattern shown in FIGS. **13**, **18** and **24** is provided for illustrative purposes and no claim is made to any particular material.
